Primary Examiner — Marcus Jackson

(74) Attorney, Agent, or Firm — Meunier Carlin & Curfman LLC

(57) **CLAIM**

The ornamental design for a filament, as shown and described.

DESCRIPTION

FIG. 1 is a perspective view of a first embodiment of our new design;

FIG. 2 is a front view of the design shown in FIG. 1, the rear view being a mirror image of the front view;

FIG. 3 is a left side view of the design shown in FIG. 1, the right side view being a mirror image of the left side view;

FIG. 4 is a top view of the design shown in FIG. 1;

FIG. 5 is a bottom view of the design shown in FIG. 1;

FIG. 6 is a perspective view of a second embodiment of our new design;

FIG. 7 is a front view of the design shown in FIG. 6, the rear view being a mirror image of the front view;

FIG. 8 is a left side view of the design shown in FIG. 6, the right side view being a mirror image of the left side view;

FIG. 9 is a top view of the design shown in FIG. 6; and,

FIG. 10 is a bottom view of the design shown in FIG. 6.

The break lines are shown to indicate indeterminate length. The dashed broken lines shown in the drawings form no part of the claimed design.

1 Claim, 10 Drawing Sheets# US D841,838 S
